UNITED STATES PATENT OFFICE

2,077,097

RIVETING MACHINE

Herman H. Diehl, Huntington, W. Va., assignor
to The West Virginia Rail Company, a corpora-
tion of West Virginia

Application April 29, 1936, Serial No. 77,038

10 Claims. (Cl. 29—33)

My invention relates more particularly, though not exclusively, to riveting machines, especially of a type wherein the riveting is performed by roller means, for attaching to fence posts, the 5 studs at which the wires or wire fencing of the fence are secured.

One of my objects is to provide a riveting machine particularly for the especial purpose above referred to by which the operation of riveting 10 the studs in place may be quickly, positively, and easily performed.

Another object is to provide a machine for producing on fence posts studs having angularly disposed portions extending lengthwise of the 15 posts for the attachment thereto of the wires or wire fencing to be assembled with the posts for producing a fence, and to provide in the same machine for the riveting of the studs in place and the bending of the same to produce the angularly extending portions above referred to.

Another object is to provide a machine in which the studs, riveted in place, are bent at the proper place and preferably in the single passage of the work through the machine.

Another object is to provide a machine in which 25 studs may be riveted in place, and their free ends preferably bent into angular position regardless of the number of studs and their spacing without requiring any adjustments of the machine for different stud-spacing.

Another object is to provide a machine by which the studs are always bent alike and in the proper direction and on the center line of the posts.

Another object is to provide a machine whereby 35 the posts to which the rivet-studs are to be applied may follow each other through the machine continuously and thus make for great speed of operation.

Another object is to provide for the riveting of 40 the studs with any desired degree of tightness.

Another object is to provide a machine in which the free ends of the studs may be bent to any 45 desired angular position; and other objects as will be manifest from the following description.

45 Referring to the accompanying drawings:

Figure 1 is a view in side elevation, with certain portions thereof broken away, of a machine embodying my invention.

Figure 2 is an enlarged section taken at the 50 line 2 on Fig. 1 and viewed in the direction of the arrow.

Figure 3 is a fragmentary view in side elevation of a portion of the structure and the work shown in Fig. 2.

55 Figure 4 is a view in end elevation of the ma-

chine of Fig. 1 viewing it from the left-hand end thereof with certain parts broken away and with the support for the work shown in section.

Figure 5 is a view in elevation of the riveting rolls with the work in position therebetween, the 5 post element of which is shown in section.

Figure 6 is an enlarged fragmentary face view of a portion of the post showing the stud positioned therein prior to the operation thereon by the riveting mechanism.

Figure 7 is a similar view of the structure of Fig. 6 showing the structure after the riveting operation.

Figure 8 is an enlarged broken longitudinal sectional view taken at the line 8 on Fig. 4 and 15 viewed in the direction of the arrow.

Figure 9 is a fragmentary view in side elevation of the stud bending rollers showing the work interposed therebetween and one of the studs in the course of being bent.

Figure 10 is a view in elevation of the two bending rolls with the work interposed therebetween and showing the stud bent to its final angular position; and

Figure 11, a broken view in side elevation of 25 the post and one of the rivet-studs shown as secured to, and bent, to final position, by the machine of the preceding figures.

As a preface to a description of the particular illustrated machine, it may be stated that the 30 fence posts shown at 12 and to which the rivet-studs are to be secured at spaced apart intervals therealong, is of channel form and the rivet-studs are to be applied to the web portion 13 of the channel.

The studs to be secured to the post for forming 35 the attaching studs for the wires or wire fencing, one of which is shown at 14, are of a form, more particularly as shown in Fig. 2 presenting a head 15 and a circumferentially thickened portion 16 40 adjacent thereto. In practice the web 13 would be provided with openings 17 therein of a size slightly larger than the portions 16 of the studs, but smaller than the heads 15, into which the studs are inserted from the interior of the channel to extend at their portions 16 in these openings with the heads 15 flatwise opposing the undersurface of the web 13; a separable filler bar 18 containing a longitudinally extending groove 19 registering with the heads 15 being positioned 50 within the channel 12 for preventing accidental dislocation of the studs.

Referring now to the illustrated machine, it 55 comprises a bed 20 having at one end a table 21 carrying an upwardly extending rib 22 extending

lengthwise of the machine, grooved along its upper surface as in the case of the member 18 and of cross sectional dimensions substantially the same as that portion of the member 18 which 5 extends into the channel of the post 12, the rib 22 being provided to receive the post 12 with the studs positioned thereon as above stated by sliding the post with the studs from the filler bar 18, positioned in alignment therewith by the operator, to the guide rib 22 in the feeding of the post and studs to the operating parts of the machine.

Located in front of the guide rib 22 and in alignment therewith are means for riveting the rivet-studs in place on the post, these means comprising an upper roll 23 and a lower roll 24, the lower roll 24 being journaled at shafts 25 and 26 thereon in stationary journal boxes 27 and 28, respectively, carried by the bed 20. The roll 23 15 which is positioned directly above the roll 24 is journaled at shafts 29 and 30 in journal boxes 31 and 32 slidably mounted on vertical uprights 33. Coiled springs, one of which is represented at 34, are interposed between the journal boxes 27 and 25 31, and 28 and 32. Adjusting screws 35 threaded in a stationary part of the machine and bearing 30 against the upper sides of the journal boxes 31 and 32 afford a means for adjusting the spacing of the rolls 23 and 24 in opposition to the action of the springs 34 tending to separate these rolls.

The lower roll 24 is provided circumferentially with an annular rib 36, the cross sectional contour of which is of substantially the same size and shape as that of the space defined by the channel in the post, whereby as the post, with the rivet studs thereon, is fed into the space between the rolls 23 and 24, the channel of the post will receive the rib 36 as shown, this rib containing a circumferential groove 37 of substantially the same width and depth as the width and thickness of the heads 15 of the rivet studs which thus become positioned in the groove 37 as shown.

The roll 23 contains a deep annular groove 38 about its circumference, this groove which is of 45 such depth as to cause its bottom wall 39 to clear the upper ends of the rivet studs, being of a width slightly greater than the diameter of the shank portion of the rivet stud, but of less width than the diameter of the portion 16 of the rivet 50 stud.

The roll 24 would be adjusted to such an elevation as to cause it to engage the upper ends of the enlargement 16 of the rivet studs as they are moved into position between the rolls 23 and 55 24, and mash down portions of the enlargements 16 at opposite sides of the shank portions of the rivet studs thus upsetting them against the upper surface of the post as represented at 40 (Figs. 5 and 7) thereby riveting the rivet studs in place 60 in the posts.

The rolls 23 and 24 may be driven in any suitable way as for example by means of a motor 41 mounted on the bed 20 and driving, through reduction gear mechanism (not shown) located 65 in a gear box 42, a shaft 43 connected with the shaft 30, the shafts 30 and 26 being connected together by gears 44 and 45 of the same size whereby the rolls 23 and 24 are rotated in opposite directions as indicated by the arrows in Fig. 1.

70 Located at the entrance side of the rolls 23 and 24 are guide means for insuring the entry of the ends of the rivet-studs into the groove 38 in roll 23, these means, in the particular construction shown, comprising a pair of bars 100 of 75 angle shape and reversely positioned as shown

in Fig. 4 and supported at their depending flanges 101 on the table 21 at opposite sides of the rib 22 and spaced throughout their extent from this rib 22. The horizontal flanges 102 of the bars 100 are spaced apart as shown in Fig. 4 to provide 5 a slot 103 for the rivets in line with the groove 38, the entrance end of the slot 103 being formed with a flaring throat 104 to guide the rivet studs into the narrower portion of the slot 103.

Located in front of the riveting mechanism 10 described is mechanism for bending the free upwardly extending ends of the rivet studs into angular position as for example as shown at 14 in Fig. 11, these means comprising upper and lower rolls 46 and 47.

15 The lower roll 47 is journaled at shafts 48 and 49 on its ends, in stationary journal boxes on the machine, one of which is shown at 50. The upper roll 46 which is located above the roll 47 is journaled at shafts 51 and 52 in journal boxes 20 53 and 54 slidably mounted in vertical uprights 55 and 56. Coiled springs, one shown at 57, are interposed between the vertically movable journal boxes 53 and 54 and the stationary journal boxes. Adjusting screws 58 threaded in a 25 stationary part of the machine and bearing against the upper sides of the slidable journal boxes 53 and 54 afford a means of adjusting the spacing of the rolls 46 and 47 in opposition to the action of the springs 57 tending to separate these rolls.

The roll 47 is a duplicate of the roll 24, the circumferential rib of the roll 47 being represented at 51 and its annular circumferential groove at 60. The upper roll 46 is circumferentially grooved as represented at 61 to adapt it to fit over, and partially encompass, the upper portion of the post as shown in Fig. 10. The bottom of the groove 61 contains a succession of grooves 62 and 63, the groove 62 being of a 40 width slightly greater than the width of the rivet stud, measured through the portions 40 thereof. The groove 63 is of a width slightly greater than the diameter of the shank portion of the rivet stud and of a depth considerably 45 greater than the depth of the groove 62 and defining the width of the spaces between the angularly extending portions 14 of the rivet 50 studs and the adjacent face of the post, in the finished structure.

In operation the post with the rivet studs riveted thereto by the riveting mechanism described, are fed into the space between the rolls 46 and 47, these rolls gripping the post and exerting a feeding action thereon and operating as 55 the upper ends of the rivet studs move into engagement with the bottom wall of the groove 63, to bend these ends over into the position shown in Figs. 8, 10 and 11.

The roll 47 may be driven in any suitable way, 60 as for example through the medium of an endless sprocket chain 66 engaging sprockets 67 and 68 on the rolls 24 and 47, respectively.

As will be understood from the foregoing, the post after once being fed into the bite of the 65 rolls 23 and 24 is automatically fed through the machine by the action of these rolls and the rolls 46 and 47 from which latter they are delivered to a supporting roll 69 journaled at the feed-out end of the machine, the roll 69 being 70 mounted for vertical adjustment to insure perfectly straight delivery of the posts.

While I have illustrated and described a particular construction of machine embodying my invention I do not wish to be understood as in- 75

tending to limit it thereto, as the same may be variously modified and altered and the invention embodied in other forms of structure within the spirit thereof. Thus by way of examples, 5 the posts to which the studs are to be attached may be of other cross-sectional shape than that shown in which event the contours of the riveting and bending rolls would be correspondingly altered; and if desired, the posts with the rivets 10 preliminarily positioned thereon may be fed into the machine in inverted position, namely, with the webs of the channels lowermost, in which event the filler bar 18 may be eliminated and the riveting and bending roll mechanism would 15 be inverted to cause the rolls 24 and 47 to be the upper rolls and the rolls 23 and 46 to be the lower rolls.

What I claim as new and desire to secure by Letters Patent, is:

20 1. Riveting means comprising members for receiving rivets between them and setting the rivets, one of said members being in the form of a roll having a peripheral groove to receive ends of the rivets, said groove being of a width less than the thickness of those portions of the rivets which are to be upset.

25 2. Riveting means comprising rolls for receiving rivets between them, one of said rolls having a peripheral groove to receive ends of the rivets, said groove being of a width less than the thickness of those portions of the rivets which are to be upset.

30 3. Riveting means for riveting in place rivets having shanks with enlargements at the portions thereof at which they are to be upset, comprising members for receiving the rivets between them and setting the rivets, one of said members being in the form of a roll having a peripheral groove to receive the ends of said shanks 35 and of a width less than the thickness of said enlargements, whereby said means operate to upset the rivets at said enlargements.

40 4. A machine for bending studs on stud-equipped articles comprising members between which the articles are passed, one of said members having a groove to receive the outer ends of the studs, the distance from the bottom of said groove to the opposing face of the other of said members being less than the thickness of said articles measured at their stud-equipped portions.

5 5. A machine for bending studs on stud-equipped articles comprising members between which the articles are passed, one of said members being in the form of a roll having a peripheral groove to receive the outer ends of the studs, the distance from the bottom of said groove to the opposing face of the other of said members being less than the thickness of said articles measured at their stud-equipped portions.

10 6. In a machine of the character set forth, the combination of means for riveting studs to an article and means, located beyond said first-named means and to which the articles with the rivets riveted thereon are delivered, for bending the studs into angular position.

15 7. In a machine of the character set forth, the combination of rotary means for riveting studs to an article and rotary means located beyond said first-named means and to which the articles with the rivets riveted thereon are delivered, for bending the studs into angular position.

20 8. A riveting machine comprising a combined rivet-retainer and guide for apertured bars to which rivets are to be secured and in which apertures headed rivets are positioned with their heads lowermost and along which said bars, with the rivets assembled therewith and bearing on said guide, are movable, and riveting means at an end of said guide adapted to receive the assembled bars and rivets from said guide.

25 9. The method of assembling apertured bars and headed rivets in said apertures and setting the rivets, which comprises inserting the rivets into said apertures, assembling with said bars, to engage the heads of the rivets, means, separate from said bars, for holding the rivets from dropping out of said apertures, sliding the bars, with the rivets thereon, along said means and out of engagement therewith, maintaining the rivets in place after leaving said means, and upsetting portions of said rivets to secure them in place on said bars.

30 10. Riveting means comprising opposed rolls journaled to rotate about substantially parallel stationary axes, one of said rolls formed to support a rivet and the remaining roll formed to upset a rivet supported by the first named roll.

35 HERMAN H. DIEHL. 40 50
